UNITED STATES PATENT OFFICE.

JOHN B. DRUMM, OF WINSLOW, ARIZONA, ASSIGNOR OF FORTY-NINE ONE-HUNDREDTHS
TO GEORGE L. DRUMM, OF BARSTOW, CALIFORNIA.

ELECTRIC-LIGHT-EXTENSION DEVICE.

1,268,102.

Specification of Letters Patent.

Patented June 4, 1918.

Application filed August 31, 1914. Serial No. 859,470.

To all whom it may concern:

Be it known that I, JOHN B. DRUMM, a citizen of the United States, residing at Winslow, in the county of Navajo, State of 5 Arizona, have invented certain new and useful Improvements in Electric-Light-Extension Devices; and I do hereby declare the following to be a full, clear, and exact description of the invention, such as will enable others skilled in the art to which it 10 appertains to make and use the same.

This invention relates to an electric light extension device.

It is the object of my invention to simplify and otherwise improve the structure, and to increase the efficiency of devices of this character and it is more particularly my object to provide a compact drum mounting wherein connections between service 15 wires and wires wound on the drum are maintained upon rotation of the drum, and wherein the contacts employed in effecting these connections are completely housed.

With the above objects in view such as 20 will appear as my description progresses, my invention comprises the combination and arrangement of parts as set forth in and falling within the scope of the appended 25 claim.

Referring to the drawings:

Figure 1 is a side elevation of my device, Fig. 2 is a longitudinal sectional view thereof,

Fig. 3, a section on line 3—3 of Fig. 1, and Fig. 4, a section on line 4—4 of Fig. 7.

Fig. 5 is a section on line 5—5 of Fig. 7.

Fig. 6 is a section on line 6—6 of Fig. 7.

Fig. 7 is an enlarged sectional view 30 through the winding drum, and

Fig. 8 is a bottom plan view of the uppermost contacting disk.

Referring to the drawing by reference characters wherein like parts are indicated by like characters throughout the several 45 views:

My device comprises a U-shaped bracket 1 which is adapted to be secured to the ceiling of a room. On the bight portion of this U-shaped bracket is mounted a contact 50 disk 2 which is rigidly secured in place on a hub 3 which extends through a hole in the said bight portion and binds on the edges thereof.

The rosette 4 from which the current is 5 transmitted to the device is secured to the

ceiling between the legs of the U-shaped member 1 and the wires 5 from the said rosette are attached to the disk 2 at diametrically opposite points in a manner which will now be described.

The disk 2 is of cup-shape and is made of suitable metal of which the conductivity is high. The interior of this disk 2 is alined with insulating material 6 and mounted within the said disk are alternate rings of 60 metal and insulation indicated by the reference characters 7 and 8, respectively. One of the wires 5 is connected to the outermost metallic ring 7 while the other wire 5 is connected to the innermost ring 7, the said 70 wires being extended through holes in the disk 2 and the outer insulating ring 8.

A revoluble disk 9 is mounted on the first mentioned disk and the under face of the said disk contacts with the upper face of 75 the first mentioned disk. The construction of this disk is similar to the construction of the disk 2 inasmuch as it has corresponding rings of metal and insulating material, the metal rings contacting with the metal 80 rings on the disk 2.

In order that there may be a great amount of contacting surface between the rings on the disk 2 and the disk 9, I have provided grooves 10 in the rings 7 on the disk 2, while 85 on the metallic rings of the disks 9, I have provided tongues 11 which fit into the grooves 10 on the first mentioned rings and thus not only providing greater contacting surface, but also insure a positive contact.

A downwardly extending sleeve 12, projects through a hole in the disk 2 and the hub 3 and has a longitudinally extending hole 12' therethrough which terminates at its lower end in openings 13 located at diametrically opposite points on the said sleeve.

A wire 14 is connected to the innermost ring of the disk 9 and extends downwardly through the hole 12' in the sleeve 12 and thence outwardly through one of the openings 13 and a second wire 15 is connected to the outermost metallic ring of the disk 9 and likewise extends downwardly through the hole in the sleeve 12 and out of the other opening 13.

Fixedly connected to the lower end of the sleeve 12 is an inverted U-shaped bracket 16 which is made of any desirable spring metal. Rotatably mounted between the legs of the U-shaped member 16 on axle 17 is a drum 110

18. Secured to the ends of the legs of the U-shaped member 16 are disks 19 which have holes therethrough registering with the holes in the adjacent legs, through which holes the axle 17 passes.

These disks 19 are composed of outer rings 20 and inner rings 21 which are insulated from each other by an insulating ring 22 of suitable material. The inner ring 21 has an inwardly projecting shank 21' which contacts with the inner face of a metallic ring 23 in one of the hubs 24 of the drum 18, the said ring being insulated from the outer portion of the hub by a ring 25 of suitable insulating material. See Fig. 5.

The ends of the wires 14 and 15, see Fig. 4, pass through holes in the outer ring 20 of the disks 19 and are connected to the innermost ring 21 so that the current flowing through one of the said wires will be transmitted to the ring 23 on one of the hubs, see Fig. 5, and will be conducted from the ring 23 on the other hub inasmuch as the ring 23 and the ring 21 on the disk 19 are always in contact with each other.

To each of the rings 23 is connected a wire 26 which passes through the adjacent flange of the drum 18 and is connected between the flanges to one wire of a double wire cord 27, which cord is adapted to be wound upon the drum when the light is not used, but which is adapted to be unwound from the drum when it is desirable to extend the light to a distant point.

These disks 19 are insulated from the legs of the U-shaped bracket 16 by a sheet of mica 28 or any other suitable insulating material.

The wires in the cord 27 are connected to 40 a lamp socket 29 which is supported on a suitable stand 30, the said stand having thumb-shaped rubber suction pads 31 on the lower ends thereof so that the stand may be supported in a horizontal position by allowing these suction pads 31 to clamp upon a mirror or other smooth surface.

Thus it may be seen that the current is carried through one of the wires 5 from the rosette 4 to the ring 7 of the disk 2 and is then carried through the contacting of the disks 2 and 9 to the wire 14 through which the current is carried to one of the disks 19 and thence to one of the wires of the double wire cords 28. The current is then carried through the lamp and back to the other disk 19 and thence through the disks 2 and 9, being conducted by the proper rings therein, and again through the other wire 5 back to the source.

60 When it is desirable to carry the lamp on the stand to a point remote from the supporting device it is only necessary to grasp

the stand and the drum 18 will revolve in its bearings and allow the cord 28 to be pulled therefrom and because of the fact that the 65 disks 19 contact with the rings 21 on the said drum there are no wire connections between the movable drum and the bracket 16 and consequently there will be no tendency of these wires becoming broken. The lamp 70 may be also moved about a circle with the sleeve 12 as a pivot and with this motion there will be no tendency to break the wires as the disks 2 and 9 act as contacts and there is no positive wire connection between 75 any of the movable parts and the stationary parts.

In order that the cord 28 may be automatically wound upon the drum 18 when the lamp is released, I have provided in the said 80 drum a plurality of diametrically opposite slots in which are slidable mounted gravity actuated pawls 32 which are adapted to engage in a longitudinal slot in the axle 17 to maintain the said drum in any of its plurality of positions, but which when the drum is rapidly rotated will fly outwardly against the periphery of the drum by centrifugal force and will therefore allow the drum to 90 rotate on the axle.

A coil spring 34 is secured to the inner face of the drum and also to the axle 17 so that when the pawls are released by a sudden jerk on the drum, the said spring will then wind the cord 28 in the channel of the 95 drum.

What is claimed is:—

An electric wire extension device comprising a bracket including spaced arms, a shaft carried by said arms, a drum mounted 100 on the shaft, contact rings mounted on the shaft at the sides of the drum, contact rings carried by the drum in contact with the first-named rings, wires leading from the drum contact rings, wires leading from the first-named contact rings, and an inner and outer bearing-ring disposed between the drum and each bracket-arm and secured to 105 said drum and bracket arm respectively, insulations disposed between the outer bearing-rings and the first-named contact rings, insulations disposed between the inner bearing rings and the drum bearing contact rings, and insulation plates between the first-named contact rings and the bracket-arms, 110 the peripheries of said rings lying inwardly of the edges of the bracket-arms.

In testimony whereof I affix my signature, in the presence of two witnesses.

JOHN B. DRUMM.
